BY *H. G. Stahlbach*

ATTORNEY.

UNITED STATES PATENT OFFICE.

JOHN W. HORNBERGER, OF SHILLINGTON, PENNSYLVANIA, ASSIGNOR TO READING HARDWARE CORPORATION, A CORPORATION OF PENNSYLVANIA.

DOOR CLOSER.

Application filed January 27, 1927. Serial No. 163,890.

My invention is particularly adapted to door closers such as are commonly employed in connection with checking means for controlling the spring action; but my improvements relate especially to the spring mechanism thereof, the general purpose being to provide a simply and satisfactorily constructed closer which will be most advantageously operative and which will also be applicable to either right or left hand doors without any change in the standardized parts or their arrangement.

Door closers have commonly employed a coiled spring the tensioning of which is increased by opening of the door to which they are connected, and provision has heretofore been made for effecting such tensioning of the spring from one end or the other thereof as determined by the right or left hand swinging of the door to which the closer is applied. In my improved construction this is accomplished very simply and satisfactorily, without involving any changing of the fixedly assembled structure, and with provision for normally maintaining the assembled parts in neutral position under desired minimum spring tension preliminary to applying the closer to either a right or left hand door; as fully described in connection with the accompanying drawings illustrating a preferred embodiment of the invention, the novel features of which are clearly defined in the subjoined claims.

Fig. 1 is mainly a vertical longitudinal section of my improved door closer, shown in connection with a checking mechanism commonly employed.

Fig. 2 is a cross-sectional view on the line 2—2 of Fig. 1; the coiled spring being indicated without unduly obstructing the view below it.

Figs. 3 and 4 are separate plan views of the spindle sleeve and casing cap respectively; the sleeve showing being modified.

Fig. 5 indicates a modification of the preferred construction.

Fig. 1 illustrates a common form of spring casing 1, combined with a horizontal check cylinder 2; the door-operated spindle 4 being mounted in the bottom closure 3 of the casing, and having a crank connection 5 to the check piston 6 which controls the action of the door closing spring. As already stated my improvements relate to the door-closing spring mechanism shown in connec-

tion with the casing 1, the spindle 4 therein being merely represented as extending below its suitable mounting in the bottom closure 3 of the casing for operating the check piston as is commonly desired.

In my improved construction as shown, an ordinary coiled-plate spring 18 is employed to effect the required closing action upon the door-connected spindle arm 11; such closing tension being imparted to the spring by causing any movement of the door-connected arm 11, from a neutral or state-of-rest position, to tighten the spring by a winding-up action thereon either at its inner or outer end, as determined by the direction of movement of said arm with the swinging door.

As shown the inner end of the spring is engaged in a recess 8^a of a sleeve 8 mounted directly upon the spindle 4; while its other end is similarly engaged by an outer cylindrical carrier 15 therefor which rests upon the bottom closure 3 of the casing chamber and is rotatably fitted to the wall of the latter independently of the spindle. The turning of the spindle 4 by movement of its fixedly attached door-connecting arm 11 in one direction, is arranged to impart a corresponding winding-up movement to the rotatable spindle sleeve 8,—this being effected as shown by contact of the swinging arm 11 with a projecting pin 10 in the flange portion 8^b of the sleeve; while an opposite swinging movement of said arm 11 is arranged to impart a corresponding winding-up movement to the outer spring carrier 15,—this being effected by a spindle arm 4^a extending radially within the casing so as to engage the inward projecting rotating contact 15^a on the carrier. The ends of the coiled-plate spring as shown, provide a vertically extended engagement with the sleeve 8 and the outer carrier 15.

In order to make such winding-up movements upon one end respectively of the spring, effective in increasing the tension, it is of course essential in each case that the other spring end be fixed during such movement; and my improved construction provides for effecting this very simply by means of separate fixed stops 21 and 20 on the casing, respectively for the outer spring carrier 15 and the inner sleeve carrier 8. As shown, the inner periphery of the bottom flange 15^b of the outer carrier 15 is so shaped

as to provide a stop shoulder 15^c adapted to contact with a fixed projection 21 on the bottom closure 3, so as to prevent rotation of the carrier beyond such fixed stop 21 but permitting free rotation thereof in the opposite direction. The top flange 8^b on the spindle sleeve 8, rotatable in one direction with the door-connecting spindle arm 11 by means of the upwardly projecting contact pin 10, is 10 positively stopped in the other direction by said fixed stop 20, which is engaged, as indicated, by a downward extension 10^a of said contact pin.

The fixed stop 20, as shown, is provided 15 on the top face of a casing cap 22, which is removably fitted to the top of the casing 1 but is secured thereto, as by set screw 22^b, so as to normally constitute a fixed part of the casing and provide a fixed support for the 20 flanged spindle sleeve 8 resting upon it, and also a fixed upper bearing for the spindle 4; the latter function being effected through the spindle sleeve 8, which is rotatable in a fitted central aperture of the cap as well as upon 25 the spindle 4. Obviously however, this fixed stop 20 may be provided directly upon the casing 1 instead of upon a cap 22 therefor, as is indicated at b² in Fig. 5, which figure also shows the integral flange 8^d of the rotary spindle sleeve 8 as adapted to itself form a casing cap. The fact that the sleeve cap 8^d of the Fig. 5 showing, is rotatable by the door-connecting arm 11 of spindle 4 as limited by the casing stop 20^b, does not prevent 30 its functioning as an upper bearing for the spindle 4 or affect the essential operation as hereinafter further described.

In the assembling of the parts of my improved closer, a normal or minimum operating tension is put upon the spring 18; 40 which tension may be varied as required to suit different doors, but in any case sets the movable parts in determined relative position. This normal state-of-rest position of the parts is changed by movement of the door-connected spindle arm 11 in either direction, with resulting increased tensioning of the 45 spring.

In my improved construction as shown, 50 this normal tensioning of the spring is variable by means of a circular series of pin holes 8^c in the spindle-sleeve flange 8^b, into one or another of which holes the contact pin 10, 10^a is dropped when the sleeve has been 55 turned by means of a suitable wrench so as to impart the desired tension; the outer end of the spring being held immovable by engagement of its outer carrier 15 with the casing stop 21, and the pin extension 10^a being held 60 in contact with the casing stop 20 when the determined tension is secured. In the state 65 of rest under normal tension which is thus secured, the door-connected spindle arm 11 is normally pressed against the contact pin 10 of the spring engaged spindle sleeve 8,

while the latter is held against rotation by engagement of its depending pin portion 10^a with the casing stop 20; the outer spring carrier 15 being pressed against the fixed casing stop 21, and having its inward projection 15^a 70 pressing against the inner spindle arm 4^a so as to normally press the door-connected spindle arm 11 against the pin 10 as stated.

The operation of my attached closer involves merely the turning of the spindle arm 75 11 in one direction or the other as determined by the swing of the door, with resulting increase of the spring tension respectively by turning of the sleeve 8 while the outer carrier 15 is held by casing stop 21, or by turning 80 of the outer carrier 15 while the sleeve is held by casing stop 20. The essential construction of my closer is equally simple and satisfactory, and the details thereof may be readily modified within the scope of my invention as 85 defined in the claims.

What I claim is:

1. A door closer comprising a coiled-plate spring; a cylindrical casing therefor having fixed top and bottom closures and stop contacts; a centrally mounted spindle having fixed thereto a door-connected lever and an interior radial arm; a spring-tensioning sleeve rotatable directly upon said spindle with limitation in one direction by said top stop-contact and having a lever-engaging projection contact; and a cylindrical spring-tensioning carrier rotatably fitted to the casing wall independently of the door operated spindle, said carrier having its rotation in one 90 direction limited by said bottom stop-contact and being provided with an inwardly extending contact engageable by said radial arm; said spindle sleeve and independently mounted carrier being respectively operated tensioningly by opposite swingings of said door-connected lever.

2. In a door closer comprising a casing provided with fixed stops, a spring therein, a door-operated spindle having an interior radial arm, and a single spring-engaged sleeve upon said spindle having spring-pressed rotation thereof prevented by one of said stops but rotatable with said spindle in spring-resisted direction; a cylindrical carrier for the outer end of the spring fitted to the casing independently of the spindle said carrier being arranged to engage another of said stops to prevent spring-pressed rotation thereof and being operatively engaged by said radial arm for spring-resisted rotation.

3. In a door closer comprising a casing provided with stop contacts, a spring therein, a door-operated spindle having an interior radial arm, and a single spring-engaged sleeve upon said spindle having spring-pressed rotation thereof prevented by one of said stops but rotatable with said spindle in spring-resisted direction; a cylindrical carrier for the outer end of the spring fitted to 125

the casing independently of the spindle and engageable by said radial arm, said carrier having a shouldered flange seating in the casing and adapted to be spring-pressed 5 against one of said stop contacts.

4. A door closer comprising a casing having a bottom closure and fixed stops; a coiled-plate spring therein; a fixed spindle-supporting casing cap; a spindle mounted in said 10 bottom closure and cap and having a door-connecting arm fixed to its extending end and an inner radial arm; a flanged sleeve on said spindle turning upon said cap and engaging the inner end of the spring; and a cylindrical 15 carrier for the outer end of the spring apart from the spindle and in rotating contact with the casing wall; said carrier being adapted to engage one of said stops and to be operatively engaged by said radial arm and said 20 spindle sleeve flange having a circular series of pin holes and an adjustable pin contact therein adapted to be held in engagement with said arm and one of said fixed stops by determinedly varied spring tension.

25 5. A door closer comprising a cylindrical casing provided with a fixed bottom stop and a fixed top stop, a spindle axially mounted in said casing and having an inner radial arm and a door-connecting top arm fixed thereto, 30 a top-flanged spring-connecting sleeve rotatably mounted on said spindle above said radial arm and provided with an adjustably set pin adapted to contact with said door-connecting spindle arm and with said fixed 35 top stop, a coiled-plate spring having its inner end engaged by said rotatable sleeve, and a cylindrical rotary carrier for the outer end

of said spring rotatably fitted to the inner wall of the casing apart from the spindle and having a stop shoulder adapted to engage 40 said fixed bottom stop and an inwardly extending contact adapted to engage said radial spindle arm; said spring being normally tensioned by determined setting of said 45 spindle sleeve relative to said fixed stops, and being increasingly tensioned by door-arm rotation either of said sleeve or of said independently mounted outer carrier.

6. A door closer comprising a casing having a bottom closure and fixed top and bottom stops; a coiled-plate spring therein; a fixed spindle-supporting casing cap; a spindle mounted in said bottom closure and cap and having a radial inner arm, and a door-connecting arm fixed to its extending 50 end; a flanged sleeve on said spindle turning upon said cap and engaging the inner end of the spring; and a cylindrical carrier for the outer end of the spring apart from the 55 spindle and in rotating contact with the casing wall; said flanged spindle sleeve having projections adapted respectively to engage the swingable door-arm and said top stop, and said rotatable carrier having a stop shoulder engageable with said bottom stop 60 and an inwardly extending contact projection adapted to engage said radial inner arm, whereby the movable parts are set in determined relative positions by normal tensioning of the spring and are movable therefrom 65 against increasing tension by either right or left swinging of said door-arm.

In testimony whereof I affix my signature.
JOHN W. HORNBERGER.
